UNITED STATES PATENT OFFICE.

JOHN B. DAVIDS, OF NEW YORK, N. Y.

DESIGN FOR AN INKSTAND.

SPECIFICATION forming part of Design No. 12,981, dated June 20, 1882.

Application filed April 24, 1882. Term of patent 14 years.

To all whom it may concern:

Be it known that I, JOHN B. DAVIDS, of New York city, in the county and State of New York, have invented and produced a new and original Design for Stands for Ink and Mucilage, of which the following is a specification, reference being had to the accompanying drawings, forming a part thereof.

Figure 1 is a side elevation, and Fig. 2 a plan view, these two views being necessary to fully illustrate the design.

My stand may be made of various materials, preferably clear glass. It presents a mouth and neck of ordinary form, and alongside thereof, in the position usually occupied by the dome-shaped air-chamber or reservoir, I present the appearance of a horse's foot in an inverted position. The effect is unique and attractive.

Referring to the figures, A is the mouth, in a cup-shaped form. B is a contracted neck, and C an enlargement or well. D is a slightly narrowed junction, connecting the well with a reservoir, E, the side of which adjacent to the mouth is substantially upright and the remaining sides conical or flaring, with the large end uppermost.

The upper face is nearly level, but slightly

inclined downward toward the mouth. It is hollowed in the center and on the side toward the mouth and shaped to imitate the frog of a horse's foot in an inverted position. The extreme base represents the natural skin and hair at the junction of the hoof with the flesh.

When my design is used for mucilage a brush and cap (not represented) will usually be applied on the mouth. When for ink a correspondingly-different cover will be there attached.

My design presents a tasty appearance either thus equipped or when used alone for the same or other purposes. Small flowers standing in the well produce a particularly fine effect.

I claim—

The design for a mucilage or ink stand herein shown and described, the same consisting of the inverted horse-foot E, connected by the junction D with a suitable well and neck and with the mouth A.

JOHN B. DAVIDS.
